COMBINATION TOASTER AND OVEN OR SIMILAR ARTICLE

Paul O. Rawson, Jr., Trumbull, and John A. Russo,
Bridgeport, Conn., assignors to General Electric Com-
pany, a corporation of New York

Application March 15, 1956, Serial No. 40,622

Term of patent 14 years

(Cl. D81—10)

Fig. 1.

Fig. 2.

Fig. 3.

Fig. 4.

Fig. 1 is a front elevation view of a combination toaster and oven or similar article embodying our new design.

Fig. 2 is a top plan view thereof.

Fig. 3 is a rear elevation view thereof.

Fig. 4 is a side elevation view thereof.

The dominant features of the design reside in the portions shown in full lines.

We claim:

The ornamental design for a combination toaster and oven or similar article, substantially as shown and described.
